W. M. Roach

ATTORNEY

UNITED STATES PATENT OFFICE.

SAMUEL WILEY, OF METUCHEN, NEW JERSEY.

COMBINED FIREARM AND GRENADE DISCHARGER.

Application filed November 8, 1923. Serial No. 673,443.

(FILED UNDER THE ACT OF MARCH 3, 1883, 22 STAT. L., 625.)

To all whom it may concern:

Be it known that I, SAMUEL WILEY, a citizen of the United States, and a resident of Metuchen, county of Middlesex, and State 5 of New Jersey, have invented an Improvement in Combined Firearms and Grenade Dischargers, of which the following is a specification.

The invention described herein may be 10 used by the Government, or any of its officers or employees in prosecution of work for the Government, or by any other person in the United States, without payment to me of any royalty thereon, in accordance with 15 the act of March 3, 1883.

The subject of this invention is a combined fire arm and grenade discharger.

The primary object of my invention is 20 the provision of a fire arm which may be used for all ordinary purposes and which may be readily converted into a grenade discharger.

A further object is the provision of a fire arm in which means will be provided in the butt thereof for receiving and discharging a 25 grenade or other projectile.

With the foregoing and other objects in view, my invention resides in the novel arrangement and combination of parts and in the details of construction hereinafter described and claimed, it being understood 30 that changes in the precise embodiment of the invention herein disclosed may be made within the scope of what is claimed without departing from the spirit of the invention.

A preferred embodiment of my invention 35 is illustrated in the accompanying drawing, in which,

Fig. 1 is a view in side elevation of my combined fire arm and grenade discharger 40 in use as a grenade discharger, parts being broken away;

Fig. 2 is a plan view;

Fig. 3 is a detail showing in section a 45 portion of the stock containing the grenade firing mechanism;

Fig. 4 is a detail sectional view taken at right angles to that shown in Fig. 3;

Fig. 5 is a side elevation of the grenade firing hammer;

Fig. 6 is a view at right angles to that shown in Fig. 5; and

Fig. 7 is a detail showing the butt plate used as a foot piece and applied to the rifle barrel.

Referring to the drawing by numerals of 55 reference:

I have shown at 5 a fire arm which may be of any suitable type, preferably, however, the ordinary service Springfield or Enfield rifle. This fire arm is equipped with the 60 usual barrel or barrels 6 and with the customary trigger 7 and bolt 8. The butt 9 of the fire arm is preferably hollowed or recessed for a portion of its length as at 10 to receive a tubular steel jacket 11 which 65 opens at outer end of the butt. This jacket is adapted to receive a grenade or other projectile 12 and a propelling charge 13 used in projecting the grenade from the butt.

Any suitable firing means may be employed 70 for actuating the propelling charge. As shown, the stock of the rifle is recessed as at 14 and this recess is adapted to receive a grenade firing pin 15 which reciprocates in the recess and in an opening 16 formed in a 75 headed nut 17 screwed into the recess. A spring 18, in the preferred embodiment of my invention, surrounds the pin 15 and is interposed between the nut 17 and a flange 19 formed on the pin serving to normally maintain the pin in retracted or inoperative position.

The stock is further provided with a chamber 20 in which is pivotally mounted as on a pin 21 a firing hammer 22. The hammer 22 is actuated by means of a spring 23 which is coiled about the pin 21 and has one end attached to the hammer and the other end to a wall 24 of the stock. Pivotally mounted as at 25 on an ear 26 formed on the hammer 27 is a forked cam member 27 provided with depending lugs or tines 28 adapted to cooperate with and to butt against projections 29 formed on the hammer for a purpose which will hereinafter appear. The depending lugs 28 are rounded where they extend above the projections 29 so as to permit free swinging movement of the member 27 in one direction with respect to the hammer.

A trigger 30 pivotally mounted in the 100 chamber 20 serves to actuate the hammer. This trigger is formed with a handle 31 which may be manipulated by hand, or, to which if desired, may be attached a lanyard and is formed with a lower cam surface 32 105 adapted to cooperate with the cam surface 33 formed on the member 27.

The fire arm, which forms the subject of

my invention, may be used as an ordinary service piece in the usual manner, the trigger 7 and the bolt 8 being used to propel the customary service projectile from the barrel 6. If, however, it is desired to use this piece as a discharger for a grenade or other projectile of different caliber from that propelled from the bore 6, the grenade or other projectile is inserted together with a propelling discharge into the tubular member 11 fixed in the butt. The direction of fire is accordingly changed. With the ordinary service projectile the projectile will be expelled from the muzzle; when a grenade or similar projectile is to be fired the same will be projected from the butt. The grenade or other projectile and a propellant charge, will, as above stated, be placed in the butt. The trigger 30 being in inoperative position, when it is desired to fire the grenade or other projectile the trigger will be swung inwardly so that the cam surface 32 will cooperate with the cam surface formed on the member 27 to move the hammer, the desired distance against the action of the spring 23, this spring in the meantime storing up energy so that when the cam surface of the trigger no longer has a bearing on the cam surface of the member 27, the hammer is thrown violently rearwardly striking the pin 15 forcing the same against the action of the spring 18 rearwardly in the chamber 14 and through the nut 17 to strike the primer cap of the propelling charge which is exploded and which forces the grenade from the piece. The spring 18 serves to return the pin 15 to inoperative position after firing, the trigger being returned to inoperative position by hand, though, if desired, a spring may be used for the purpose.

A fire arm designed according to my invention, then, may be used both as an ordinary service piece and as a grenade or other large caliber projectile discharger. When used as an ordinary service piece, the trigger 30 is housed in a recess 34 formed in the stock.

If desired, when the fire arm is to be used as an ordinary service piece, the opening formed in the butt at the rear end on the tubular member 11 may be closed by any suitable type of closure member. Preferably, however, this closure member will serve two purposes. As shown, a member 35 may be provided, which in the preferred embodiment of my invention, is formed with a split sleeve 36 adapted to be received within the jacket 11 when the piece is to be used as a service weapon and to surround the barrel 6 at the muzzle end thereof when the piece is to be used as a grenade or other projectile discharger. For retaining the closure member in position in this latter use the sleeve portion is formed with opposed lugs 37 adapted to receive a bolt 38 which cooper-

ates with a butterfly nut serving to fasten the sleeve securely upon the barrel 6 the foresight 40 being disposed in the opening formed by the split. The closure member 35 is formed with an extension 39 which normally covers the butt in service use and which serves as a foot piece when the fire arm is used as a grenade or other projectile discharger.

If desired, to prevent scratching of the muzzle, the butt plate may be supplied with a rubber pad 41 against which the muzzle end of the barrel may rest.

While the closure is preferably formed in the manner described, any other suitable type of closure may be employed, and, similarly, the closure may be attached to any desired portion of the rifle barrel.

As heretofore stated, the discharging mechanism in the butt may be employed to propel a grenade or any other suitable type of projectile therefrom. The opening in the butt may be in any desired portion thereof and the direction of fire may accordingly be altered.

While my device is preferably employed with a rifle or similar weapon, it is by no means intended to limit my invention to this use in as much as the butt of the ordinary service pistol may be constructed so as to function as a grenade discharger in the manner described above.

The firing mechanism employed in connection with the grenade discharger may be of any suitable type and I do not intend to limit my invention to use only with firing mechanism of the type described.

I claim:

1. A combined fire arm and grenade discharger embodying a fire arm provided with the usual barrel and firing means and with a butt open at the rear end and hollowed so as to receive a grenade or other projectile, means on the fire arm for firing the grenade or other projectile rearwardly from the butt, a removable closure for the opening in the butt, said closure being provided with a projection adapted to enter the hollowed portion of the butt when the fire arm is used as an ordinary service weapon, said closure being further formed with a member adapted to extend externally of the butt to serve as a butt plate when the fire arm is used as an ordinary service weapon, said member being detachable from the butt and attachable to the barrel to serve as a foot piece when the fire arm is used as a grenade discharger.

2. A combined fire arm and grenade discharger embodying a fire arm provided with the usual barrel and firing means, and with a butt open at the rear end hollowed so as to receive a grenade, means on the fire arm for firing the grenade rearwardly from the butt and means closing the opening in the

butt when the fire arm is used as an ordinary service weapon, said closure means being removable and attachable to the barrel adjacent the muzzle thereof to serve as a foot piece for the fire arm when the same is used as a grenade discharger.

3. A combined fire arm and grenade discharger embodying a fire arm provided with the usual barrel and firing means and with a butt hollowed so as to receive a grenade, means on the fire arm for firing the grenade from the butt and means for closing the opening in the butt when the fire arm is used as an ordinary fire arm, said closure means being removable and attachable to the barrel to form a foot piece for the fire arm when the same is used as a grenade discharger.

4. A combined fire arm and grenade discharger embodying a fire arm provided with the usual barrel and firing means and with a butt hollowed so as to receive a grenade, means on the fire arm for firing the grenade from the butt and means for closing the opening in the butt when the fire arm is used as an ordinary service weapon.

5. A combined fire arm and grenade discharger embodying a fire arm provided with the usual barrel and firing means and with a butt open at the rear end and hollowed so as to receive a grenade and means on the fire arm for firing the grenade rearwardly from the butt.

6. A combined fire arm and grenade dis-

charger embodying a fire arm provided with the usual barrel and firing means and with a butt adapted to receive a grenade and means on the fire arm for firing the grenade from the butt.

7. A combined fire arm and grenade discharger embodying a fire arm provided with the usual barrel and firing means and with a butt hollowed so as to receive a grenade, a firing pin reciprocably mounted in the butt, resilient means normally maintaining said firing pin in inoperative position, a spring actuated hammer mounted on the fire arm and adapted to actuate said pin to discharge said grenade, a cam lug mounted on the hammer, a trigger, said trigger and lug being provided with cooperating cam faces, the trigger and lug normally maintaining the hammer in inoperative position, the trigger being movable to move the lug and hammer to actuate the firing pin against the action of the resilient member.

8. A combined fire arm and grenade discharger embodying a fire arm provided with the usual barrel and firing means and with a butt adapted to receive a grenade and self-cocking means for firing the grenade from the butt.

9. A combined fire arm and grenade discharger embodying a fire arm adapted to be used as an ordinary service weapon and provided with a butt having means for discharging a grenade therefrom.

SAMUEL WILEY.
